US00D811651S

(12) **United States Design Patent** (10) Patent No.: **US D811,651 S**
(45) Date of Patent: **** Feb. 27, 2018**

(54) **HAND-HELD AEROSOL GENERATOR**

- (71) Applicant: **Philip Morris Products S.A.**,
Neuchatel (CH)
- (72) Inventors: **Aaron Abroff**, Acton, MA (US);
Gregor Mittersinker, Warwick, RI
(US); **Laurent Manca**, Grandvaux
(CH)
- (73) Assignee: **PHILIP MORRIS PRODUCTS S.A.**,
Neuchatel (CH)
- (**) Term: **15 Years**
- (21) Appl. No.: **29/553,180**
- (22) Filed: **Jan. 29, 2016**

Related U.S. Application Data

- (62) Division of application No. 29/479,202, filed on Jan. 13, 2014, now Pat. No. Des. 759,296, which is a division of application No. 29/425,439, filed on Jun. 22, 2012, now Pat. No. Des. 699,391.
